UNITED STATES PATENT OFFICE.

CLEVELAND PINKNEY, OF GEORGETOWN, SOUTH CAROLINA.

SMOKER'S PIPE.

1,258,454.

Specification of Letters Patent.

Patented Mar. 5, 1918.

Application filed April 6, 1917. Serial No. 160,225.

To all whom it may concern:

Be it known that I, CLEVELAND PINKNEY, a citizen of the United States, residing at Georgetown, in the county of Georgetown 5 and State of South Carolina, have invented new and useful Improvements in Smokers' Pipes, of which the following is a specification.

This invention comprehends improvements 10 in smokers' pipes, and relates more particularly to that class of pipe known as "bottom draft," wherein the bowl is provided with a chamber extending entirely therethrough from top to bottom and open at each end.

15 One of the objects of the invention is to provide a pipe of this nature, which in spite of its peculiar construction is not clumsy, and which possesses the same general appearance as pipes of the common type.

20 Another and more specific object of the invention resides in the provision of a "bottom draft" pipe having a smoke passage communicating with the tobacco chamber at a point adjacent the top thereof and communicating with the stem passage below the 25 tobacco chamber.

Another and more specific object of the 30 invention is to provide a pipe having a stem opening into the bowl below the tobacco chamber and having its inner end closed by a valve, which may be easily opened to permit of the stem being cleaned either by running water therethrough or by a cleaner in the usual manner.

35 With these and other objects in view, the invention consists in the construction, combination and arrangement of parts herein-after set forth and falling within the scope of the claims.

40 In the accompanying drawings:—

Figure 1 is a side elevation of the pipe.

Fig. 2 is a longitudinal sectional view of the pipe.

45 Fig. 3 is a fragmentary detail view showing the construction of the upper end of the smoke passage leading from the tobacco chamber.

Referring in detail to the drawings by 50 numerals, I designates the bowl of the pipe, which may be made in any desired shape, and which is formed with a chamber extending entirely therethrough. The upper portion 2 of the bowl chamber forms a tobacco receiving compartment, which is provided 55 at its lower end with a concavo-convex grate

3 perforated in any desired manner. The grate rests upon a shoulder 4 formed by contracting the passage through the bowl at its lower end.

Extending longitudinally through the wall 60 of the bowl parallel to the central passage thereof is a smoke flue or passage 5, communicating at its upper end with the tobacco chamber through the medium of a notch 6, and at its lower end with a smoke passage 7 65 in the stem 8. A mouth-piece 9 is threaded into the stem 8.

The inner end of the smoke passage 7, which opens into the bowl below the tobacco chamber is normally closed by a valve 10 70 threaded upon the valve rod 11, said rod extending through the wall of the bowl in alinement with the passage 7 and being provided upon its outer end with a button 12. An expansive helical spring 13 encircles the 75 rod 11 and holds the valve 10 closed when the pipe is being used.

A cover 14 is hinged, as at 15, to a band 16 surrounding the top of the bowl. This band is locked in position by a depending 80 flange 17 which fits into the groove in the outer face of the bowl. A clamping wire or ring 18 may be used to secure the flange within the groove if desired. The cover is held closed by a latch 19, but may be easily 85 swung open when desired by means of a lift 20.

Special importance is attached to the arrangement of the valve closing the flue 7, and it is to be noted that when opened a 90 straight passage is provided through which water or a cleaner may be passed to remove accumulations from the stem. It is important for sanitary reasons and essential to the perfect complete enjoyment of a smoke 95 that the stem be kept clean, and this can only be accomplished when means are provided such as shown for running a straight instrument entirely therethrough.

From the foregoing description, taken in 100 connection with the accompanying drawings, it will be apparent that I have provided a very simple, practical, and attractive "bottom draft" pipe, having a valve closed stem which may be easily and quickly cleaned 105 when the valve is opened.

While I have shown and described the preferred embodiment of my invention by way of illustration, it will be understood that minor changes in the construction and 110

arrangement of parts may be made without departing from the scope and spirit of the invention as claimed.

I claim:—

- 5 1. In a pipe for tobacco and the like, a bowl formed with a cavity, a stem on the bowl formed with a straight smoke passage opening into one side of said cavity, a valve slidably extended through the side of said bowl opposite said stem and having a head within said cavity, and resilient means normally forcing said head against the side of said bowl to close the end of said smoke passage; said bowl formed with an opening 10 below the inner end of said smoke passage, and further formed with a passage having one end opening into said cavity at a point distinct from the first mentioned passage and having the other end opening into the 15 first mentioned passage intermediately of its ends; and means whereby when said valve is closed the smoke will pass through the second mentioned passage.
2. In a smoker's pipe, a bowl having a central chamber extending entirely therethrough and open at each end, a grate positioned within said chamber forming in the upper end thereof a tobacco compartment, a stem having a straight smoke passage 20 opening into the bowl below the grate, the bowl being formed with a passage commu-

nicating with the passage in the stem and with the tobacco compartment adjacent its upper end, and a valve mounted within the lower end of the bowl passage for movement 35 toward and away from the stem to normally close the inner end of the smoke passage through the stem.

3. A smoker's pipe including a bowl having a central passage extending therethrough 40 and open at each end, a grate mounted within such passage forming in the upper end thereof a tobacco compartment, a stem extending from the bowl below the grate and having a straight smoke passage opening 45 into the bowl below said grate, a passage connecting said smoke passage with the tobacco compartment at its upper end, a valve stem alined with the smoke passage in the pipe stem and projecting through the bowl, 50 a valve on said stem, resilient means forcing said stem inwardly to normally close the valve, and a cover mounted on the upper end of the bowl, said valve when opened establishing a straight passage from the bowl 55 through the pipe stem.

In testimony whereof I affix my signature.

CLEVELAND ^{his} X PINKNEY.
